UNITED STATES PATENT OFFICE.

JAMES N. TZIBIDES, OF BEACHMONT, MASSACHUSETTS.

MACHINE FOR WRAPPING TIPS ON CIGARETTES AND THE LIKE.

1,231,814.

Specification of Letters Patent.

Patented July 3, 1917.

Application filed June 27, 1914. Serial No. 847,728.

To all whom it may concern:

Be it known that I, JAMES N. TZIBIDES, a subject of the King of Greece, residing at Beachmont, in the county of Suffolk and 5 State of Massachusetts, have invented new and useful Improvements in Machines for Wrapping Tips on Cigarettes and the like, of which the following is a specification.

This invention relates to improvements in 10 machines for placing cork tips on cigarettes. It is in the nature of an improvement on the machine shown in my Patent No. 890,734, dated June 16, 1908, to which reference is made for a fuller explanation of 15 parts where necessary. A portion of the mechanism shown in the present application is shown more in detail and is claimed in my co-pending application for patent, Serial No. 847,729, viz.: the feeding mechanism, 20 for taking cigarettes from a quantity held loosely as a supply in a magazine and arranging them singly, end to end, longitudinally on the conveyer belt which is marked 34 herein. While the invention claimed in 25 this present specification is illustrated as designed for the work of automatically applying cork tips to cigarettes, it is to be understood that the same principles may be applied to similar uses and that the structure may be changed in various respects 30 without departing from the scope of the patent as defined by the appended claims. It is the purpose of the patent to cover, in the claims, whatever features of patentable 35 novelty exist in the invention disclosed.

The special object of the mechanism here illustrated is to provide improved means for assembling and wrapping together a cigarette, a strip of cork to form the tip, and a 40 proper amount of adhesive substance. The purpose is to do this automatically, taking cigarettes from a quantity held loosely in the magazine; taking cork or other wrapper from a rolled strip; bringing the cigarettes 45 singly and successively to a place where a section of the strip is associated with them; executing a wrapping operation gradually as the cigarette and section of the strip move on together; and then depositing the completely wrapped cigarettes in a magazine whence they may be removed in quantity. The action of the mechanism is substantially 55 continuous. As a result the machine is capable of operating smoothly with a very large output per minute. The invention also comprises improvements in details of the mecha-

nism, such as the means for automatically introducing the cigarettes to the place where the wrapping is to begin, in proper position individually; severing the proper length of 60 strip, and arranging it so that the lap will come at the desired place on the cigarette, both of these features being adjustable according to the size of cigarette, length of 65 lap desired and position of lap desired. The manner of controlling the position of cigarettes and cork, to produce uniformity of results, and other details will appear hereinafter.

In the accompanying drawings:

Figure 1 is an end elevation of a machine embodying the invention;

Fig. 2 is a plan of the same;

Fig. 3 is an end elevation of certain parts on a larger scale;

Fig. 4 is a plan of certain parts on a still larger scale;

Fig. 5 is an end elevation of a fragment of the parts shown in Fig 4, with portions removed for clearness;

Fig. 6 is an end elevation of a detail of the strip handling means;

Fig. 7 is a side elevation of part of the mechanism which includes the severing blade, as it would be seen on looking toward 85 it from the left hand side of Fig. 1, on an enlarged scale;

Fig. 8 is an elevation of the same as seen from the rear;

Fig. 9 is an elevation of the same as seen 90 from the same direction as Fig. 7, but with the blade in its closed position;

Fig. 10 is an elevation of the same as seen from the rear;

Fig. 11 is a plan of the same when in the 95 position of Fig. 9;

Fig. 12 is a side elevation, in section, of the conveyer belt 34 and associated parts; and

Fig. 13 is a front elevation of the parts 100 seen in Fig. 12.

Referring to the drawings, an understanding of the general arrangement and operation of the mechanism will be facilitated by observing that a supply of cigarettes 16 is 105 contained in a holder whose nearer wall 12 and bottom 14 are seen at the rear end of the machine, and that the apparatus takes the cigarettes thence automatically to the stop 23 and thence by a rotary distributor having pockets 28, and by way of a belt 39, to a belt 34, whereon they lie end to end in single 110

file, with the leading one at the position marked A in Figs. 12, 3 and 4. When in this position it is at the forward end of the trough of which that belt forms the bottom, 5 about in the middle of Fig. 2. The leading cigarette is pushed endwise forward, Fig. 2, by a distance equal to its own length, whenever opportunity offers, into the position B, Figs. 12, 13, 3, 4, whence it is taken by the 10 main rotating drum, and, after being subject to the operation of certain appliances for positioning it precisely, is carried around that drum through the positions, C, D, E and F to G where, completely wrapped, it is 15 discharged upon a delivery plate, whence it falls to position H on a delivery belt that deposits it in the magazine M to await removal by the operator.

The action of the mechanism which 20 delivers the cigarette to position A is fully illustrated and described in my co-pending application for patent Serial No. 847,729, to which reference is hereby made for such description. Briefly, the cigarettes 16 are suit- 25 ably agitated in their supply hopper, 12, 14, so that they slide down on the bottom plate 17 in single row to a position against the stop 23, as seen in Fig. 1. Pockets 28, re- 30 volving through a path which laps past the end of plate 17, successively lift the foremost cigarette of the row, carry it over and de- 35 posit it on the guide chute 32 whence it passes by gravity to the belt 39 (lying trans- versely thereon) and is by that belt deposit- 40 ed upon the transversely running belt 34. The gearing connections between the belt 34 and the distributor 28 are such that the speed of the belt 34 carries each individual cigarette clear of the edge of belt 39 before the 45 next cigarette arrives. If unobstructed each cigarette so deposited would be carried to position A where the belt 34 terminates its horizontal course and turns down around a guide pulley 34', Figs. 4, 12, and would be projected beyond if the way were clear.

When so projected it slides into a skeleton tray 41, seen in Figs. 3, 12 and 13, and seen in part (part being broken away) in Fig. 5 until it strikes a stop 42 seen in Figs. 50 12, 3 and 4. This tray occupies an approxi- 55 mately horizontal position above the main drum 43 in a place where the cigarette can be engaged by two radially projecting pins 44 and 44' which rotate with the drum, and be carried by them, to the left, Fig. 4, until it slides off of the tray 41 at its end 41' and is thus transferred to the surface of the drum itself. The drum has any suitable 60 number of appliances for receiving and ma- nipulating the cigarette which are exact duplicates of each other, ten being represented in this case, as seen best in Fig. 3. At each of these places the drum has on its cylindri- 65 cal surface a concave recess or shallow socket 45, one of which is seen where the parts are

broken away for that purpose, at the position G in Fig. 3, so shaped as to receive and hold the cigarette in proper alinement in parallelism with the axis of drum. Coöperating with each socket 45 is a piece 45' sliding radially on the side of the drum, capable of being projected radially outward and having in its outer end a concavity 45'' adapted to register with and form a continuation of the socket 45 and to hold that part 70 of the cigarette which is wrapped with the cork tip. A pin 44' may for convenience be mounted on this sliding part, while the pin 44 is conveniently set stationary in the drum near the other end of the cigarette. These 75 two pins are in alinement with each other in the direction parallel with the axis, so that as they, traveling with the drum, rise under the tray 41 they engage the cigarette lying thereon in position B, carry it along 80 with them and off of the end of the tray, whereupon it falls into the socket 45 which is on the surface of the drum immediately in advance of those pins. Coöperating with 85 each socket 45 is a clamp having a two-part 90 upper jaw 46 working on a single pivot 46', which jaw is capable of swinging from the open position shown at the right in Fig. 3 to the closed position shown at positions C and D in Fig. 3, in order to clamp the cigarette 95 down into the socket 45 and hold it there so that it moves with the drum during the various operations that are performed upon it. Springs 46'', one of which is seen in full 100 lines at position G, Fig. 3, and which is shown on a larger scale in Fig. 5, tend to hold these jaws 46 open. A light spring rod 105 46''', projecting from the pivot 46', opposes the spring 46'' to close the jaw between the two positions that are illustrated in Fig. 5, where it engages the beginning of a fixed 110 quadrant 47, and is thereby swung upward, with the result that it simultaneously swings the jaw 46 forward and downward into position to clamp the cigarette in its socket. The quadrant is fixed adjustably in position. As the motion continues the spring rod 46''' trails along in a groove 47' in the said quadrant, holding the jaw 46 closed with an elastic pressure resulting from the slight bending of the rod by the quadrant as very 115 clearly shown in Fig. 5.

In order to position the cigarette properly before it is thus firmly clamped there are several auxiliary devices, including the stop 42 120 against which the cigarette is projected endwise from the belt 34; a discharge opening 42' for loose tobacco in tray 41 immediately under the place where the cigarette engages the stop 42; an equalizing-detent having two 125 prongs 48 of equal length and one longer prong 48' intervening between them and of greater length; and an endwise adjusting lever 49. To these may be added the spring cushioned gage 50 against which the ciga- 130

rette is pushed by the lever 49 to standardize its position just before it is clamped, and to support and close its end during the succeeding operations.

These coöperate to position the cigarette in a precisely correct location just as the clamps 46 descend upon it. The opening 42' through the tray 41 permits small particles of tobacco, which occasionally fall out of the end of the cigarette to fall through the tray 41 into the inclined spout of an under tray 42" where they slide down out of the way. In the absence of this device such small grains of tobacco are liable to accumulate on the tray 41 and to prevent the cigarette when in position B from moving to the stop 42 when projected toward it. The provision of the hole 42' would efficiently remove the bits of tobacco; but it would deposit them on the strip of gummed cork which is most conveniently positioned directly under. The introduction of this hole and of the tray located above the strip of cork prevents the occasional inclusion of a little piece of tobacco between the cigarette and its cork wrapper, which would make a defective product. This insurance for proper longitudinal positioning of the cigarette at B is coupled with a series of guides 41" which insure its proper alinement. As a result, each arriving pair of pins 44 and 44' are certain to find the cigarette in position to be taken by them; and they push it loosely along on the tines of the tray 41.

The top equalizing-detent is provided with three spring fingers. Two are of equal length, located at each end of the cigarette, so positioned as to terminate just beyond the place 41' where the cigarette has slipped off of the tray 41 and at such an elevation above the surface of the drum as to tip the oval cigarette, if necessary, so that it lies on its flatter side. They coöperate with the pins 44, 44', and the termini of tines 41' to maintain the cigarette, at moment of its dropping, standardized in parallelism with the axis of the drum, so that it falls properly into the shallow socket 45. Thereafter the middle finger 48' continues its contact with the top of the cigarette, as seen most clearly in Figs. 4 and 5, keeping it in proper position in the socket 45 by gentle pressure while the lever 49 is actuated to push it into proper position longitudinally against a stop 50. The clamp 46 meanwhile has been closing; and it reaches its clamping position just as the lever 49 reaches its final position with the cigarette properly placed for accurate assemblage with the cork strip. The lever 49 consists of a flat spring blade, seen in Fig. 4, mounted on a stationary part of the apparatus, pivoted at 49', and having a tail 49" extending forward in the direction of which the drum is moving, and lying in

position to be engaged by the pins 46' previously mentioned as they pass. It is of such length as to be engaged by each of these passing pivot pins and swung slightly on its own pivot 49' at the instant when the cigarette on which it is to act is passing its blade 49. This completes the positioning of the cigarette.

The cork strip 51 which is to be wrapped around its end comes from a supply roll 51' and passes through a suitable mechanism for applying adhesive material such as paste to it. In the form illustrated the strip of cork passes into brief contact with a roll 51" and then goes through a tension device seen in Fig. 6 and thence onward as best seen in Figs. 3 and 5 to the place where its end portion is severed from it and is associated with the cigarette just beyond the position C.

The tension device represented in Fig. 6 is a spring clamp, consisting of a little spring 52' against which an under-bar 52 presses the cork strip intermittently. The rotation of the ratchet wheel 52" is timed with respect to the rotation of the main cigarette carrying drum, so that one of the teeth of that ratchet lifts the tail of the lever 52''', on which the under bar 52 is mounted, whenever the drum is about to draw forth a portion of cork strip as hereinafter described, and suddenly releases it, thus clamping the strip to stop its motion, whenever the draft of the strip ceases and the severing mechanism acts to cut off the leading portion of the cork strip, as hereinafter described. From this spring clamp the cork strip passes over a flat support or guide 51''' which conducts it to a position close to position C of the cigarette, and supports it there with its leading end projecting to the place where the severing blades 60, 61 are shown in Fig. 3. A piece of spring wire 53 (Figs. 3, 4 and 5) presses down on the top of the strip near the end of the support 51'''. It will be understood that one edge of the strip is about in the plane of the vertical face of the drum, and that the other edge of the strip is in line with the face of the stop 50, which is the position of the end of the cigarettes. In reaching its position illustrated in Fig. 4, each stop 50 rises beside the edge of the cork strip 51, moving along with the drum and springing back a little from the face of the drum, if necessary, in order to pass the metal support 51''' of the cork strip, or the cigarette stop 42 and edge of the tray 42" under it, but it should be borne in mind that the thickness of these parts is necessarily exaggerated in Fig. 4 in order to show them and to represent the thickness of the metal, and that in reality they need not project much farther from the plane of the drum's face than does the cork strip.

A cam groove 54, seen in Fig. 4, in which a roller 54' runs, controls the position of

the slide 54'', and so moves the rod 54 carrying the jaw 55, in a direction parallel with the axis of the drum, to or from a place where it is adapted to coöperate with another jaw 56 (see Fig. 3) to seize and draw forth the cork strip. The gripping action of the jaw 55 is effected by turning the rod 54'' on which it is mounted against the tension of a spiral spring coiled thereon, and is controlled by the means seen best in Fig. 3 consisting of a cam 55' fixed above the place where the jaw is to be closed and adapted to engage and depress a lug 55'' located conveniently at a little distance from the plane of the face of the drum, as seen best in Fig. 4. The under and coöoperating jaw 56 is merely the top surface of the forward portion of the sliding piece 45', being the part which is in advance, as the drum rotates, of the socket 45''. The position of this sliding piece 45', when retracted toward the center of the drum, is illustrated at C and to the right thereof in Fig. 3, and is such that in the course of its path, rotating with the drum, the jaw 56 travels close underneath the tape 51. While it is moving in this close proximity to the tape and has nearly reached the position C, the upper jaw 55 is turned down upon it, and is held down, by the cam 55', so that the cork strip is gripped between the two jaws 55, 56 and consequently is drawn along with those jaws at the same speed at which this part of the drum is rotating. In Fig. 3 the position of the parts is represented just after this clamping has been effected. While this draft is continuing, or, preferably, after this draft has ceased, the severing blades, 60, 61 operate as described hereinafter, at the place where they are shown in Fig. 3. Their operation is timed so as to occur when the cigarette shown near them in Fig. 3, has passed them with a suitable length of the cork strip to cover the tip of the cigarette. The portion of cork thus severed travels on with the cigarette, while the slight tension imposed on the remaining strip-end by the spring 53 and the more positive tension imposed by the device shown in Fig. 6 instantly bring the main portion of the strip to rest, to await the arrival and action of the next pair of jaws 55, 56.

As the cigarette passes on from position C, being held firmly on the drum by the clamp 46, the slide 45' is pushed up by the action of cam groove 57 (Fig. 3) until at position D its socket 45'' has assembled the cork and the cigarette end closely together with the cork in intimate adhesive contact with the whole under side, of the cigarette, and with ends of the cork upstanding. The cork is held with sufficient security by being pinched adhesively under the cigarette as this operation is in process, and consequently the jaw 55 may be released, by its lug 55'' reaching the end of the cam 55' previously to the rising of the sliding piece 45'. If not, shank of jaw 55 may be elastic to permit this movement to proceed a little way before the jaw 55 is released. After such release the cam groove 54 retracts the slide 54'', and draws the jaw 55 and its lug in the direction which is downward in Fig. 4, and is toward the eye in Fig. 3, so that the brushes 58, 59 and the burnishing wheel 70 can act upon it unimpeded. These brushes are connected in any suitable way, as by belts or gearing, so that the brush 58 runs in the direction illustrated in Fig. 3 and swings upward in synchronism with the passing of the cigarettes, so as to rub against the upstanding advance flap of the cork tip between positions D and E, so wrapping that flap over the tip of the cigarette. Between the positions E and F the other brush 59, rotating in the opposite direction and moving at a speed greater than the surface of the drum but likewise in synchronism so that it registers with and acts upon every cigarette that passes, folds the rear upstanding flap down upon the forward flap. After this, between positions F and G, the burnishing wheel 70, which may preferably be a wheel with a smooth metal surface revolving in the direction of the cigarette's motion, presses and perfects the sealing operation, so that at the position G the clamps 46 may be released by the spring wire 46''' thereof reaching the end of the quadrant 47, thus releasing the cigarette and permitting it to fall from the drum to the guide plate 71 along which it is propelled by the depending pins 44, 44' in case it does not slide freely by gravity, until it reaches the end thereof and drops to position H on the delivery belt 72, whence it is carried to the magazine M to await removal by the operator and packing for shipment. Simultaneously with the release of the jaws 46 the sliding piece 45' may be moved radially inward by the cam groove 57, which is curved as at 57'' into the position where it will register with the underside of the cork strip 51 when it comes around to the top to receive and act upon another cigarette.

The severing blades, 60, 61 are actuated by mechanism which is shown in detail in Figs. 7 to 11. The blades 60, 61 work with a shearing action. They are carried on a shaft 62 which has an intermittent rocking movement of about 90° controlled by cam 63 or in any other suitable way. This cam has a groove 63' which acts upon a roller 63'' to move the connecting rod 64 backward and forward, thus rocking the gear 65 and the beveled gear 65' on the shaft 62 which meshes with it. The cam 63 may conveniently be driven by a gear 66 through the small gear seen in Fig. 1, so that it rotates once for each time a socket 45 and its asso-

ciated slide 45', jaw 55 and other parts passes the position C; and its groove 63' is so formed that the oscillation is one which throws the blades quickly downward from the horizontal and inactive position of Fig. 5 to the cutting position of Fig. 9 and then throws them back again. The termination of the downward stroke, and the initial part of the upward stroke must occur between the passing of the slide 45' and the arrival 10 of the advance part of the next jaw 55. It will be noted, as seen in Fig. 1, that the gear 65' is of considerably smaller diameter than the gear 65. The result of this is that a relatively slight change in the course of the cam groove 63' is sufficient to turn the gear 65 far enough so that the gear 65' is turned substantially through a quadrant, turning the severing blades from their inactive position 15 where they project horizontally forward into the position where they stand vertically under the shaft 62 with the cork strip between them. The severing occurs as they approach the extremity of their downward swing, which is the position illustrated in 20 Figs. 9, 10, and 11. The severing stroke is effected automatically at this part of the stroke by the construction and arrangement of parts now to be described. Rigid on the 25 rocking shaft 62 is a block 67 in which moves a slide 60' carrying the blade 60. The blade 61 is mounted on rod 61' which is supported on the same shaft, although not rigidly in one respect as will be hereinafter 30 explained. The slide and blade 60 are continually pressed toward the blade 61 by a spring 60'' strung on the rod 61'. The blades 60 and 61 are separated, when the shaft 62 is turned, by a cam 60''' which is in 35 the form of a stationary ring around the shaft 62, being fast on that portion of the frame 68 of the machine which is adjacent thereto. This cam has a bulge toward the rear. Fig. 7 shows this in the act of holding 40 the head 69'' of slide 60 to the left, thus holding the blades apart, against pressure of the spring 60''. The cam has a lower top, so that when the shaft 62 and head 69'' are to the top, as in Fig. 9, with the blades 45 down, the blade 60 is free to close upon the blade 61, so far as this cam is concerned. If such closing were controlled by the cam 60''' it would be gradual, because the slope of the cam is gradual; but the actual closing is 50 delayed until the blades have reached almost the extremity of their downward swing by a latch 69 which is pivoted on the block 67 and is pulled by a spring 69' to a position obstructing movement of the sliding head 69''. This latch and its spring, therefore, 55 hold the knives wide open during the downward swing of the blades. Displacement of the latch is occasioned close to the end of the swing of the mechanism, by the pin 71, when 60 that pin has swung from its inactive posi-

tion seen in Figs. 7 and 8 upward around the axis of the shaft 62 and to the position in which it is illustrated in Figs. 9, 10 and 11, where it is represented as having struck a stop 68' fixed on the frame 68. This pin 70 projects from the latch 69. The continued movement of the shaft 62 and the block 67 therefore throws this latch out from under the head 69'' and allows that head to descend under action of the spring 60'' pushing 75 down the blade 60. As this action occurs only in the very last small portion of the travel of these parts, it is seen that it occurs only after the blades have come into position on each side of the cork strip. As the 80 cork strip is always in a definite and closely limited path, the blades can be set with great precision so that the severing stroke is short and very quick. Consequently very little space along the drum is required, even 85 when it is rotating at relatively high speed, for the blades to be thrown into place, to do their work and to be thrown out again. The blade 60 is withdrawn from blade 61 on the upward stroke by the cam 60''', and is 90 latched there by the latch 69 when fully withdrawn. The knives may be maintained in good cutting condition, without necessity for frequent removal for sharpening, by providing a constant pressure twisting one 95 of them against the other. This is accomplished by means of the spring 72 and by the fact that the rod 61' on which the blade 61 is mounted is slightly rotatable in its support. The blade 60 is held non-rotatably 100 in its sliding bearing 67. The spring 72 is attached at one end to said bearing block, and at its other end to a pin extending from a collar fast on the rod 61'. Thus this 105 spring applies a turning moment to the rod 61' and in fact turns it as far as the rod can turn, *i. e.*, until the blade 61 is close against the blade 60. This keeps the edge of these blades rubbing together at all times.

The parts may be adjusted to provide 110 for cutting off wrappers of different length by using a cam 55' of different length, so that the distance during which the jaw 55 continues its grip and draft on the cork strip is longer or shorter. The parts may 115 be adjusted to provide for a different position of the lap of flaps of the wrapper by changing the setting of cam 63 on its shaft, so that it actuates the severing mechanism at a point more or less distant from 120 the cigarette, *i. e.*, at a greater or less time after the cigarette has passed the place where the severing occurs. In the preferred way of setting and operating the machine the cam 55' is so arranged that it releases the jaw 55 and so ceases pulling the strip before the severing mechanism acts. The latter then acts upon a stationary strip, the movement of the strip having been 125 instantly stopped by the action of the tension 130

spring 53 and clamp 52. In the interval, however brief, between the releasing of the jaw 55 and the severing, the cigarette is moving on with the drum and the strip of 5 cork under it is being held stationary. Thus, the cigarette is gradually approaching the leading end of the cork strip. This approach may be arrested by the severing of the strip, upon the occurrence of which 10 the severed portion begins instantly to move along with the cigarette. The position of the lap of the flaps will then depend upon the length of wrapper which is before the cigarette and that which is behind it. The 15 coating of paste between the severed section and the cigarette hold the two together until the sliding piece 45' rises and bends the wrapper ends up from their arrangement shown at position C to that shown at position D. As the action of the machine continues, the brush 58, whose function is to 20 wipe down the leading flap of the cigarette, may accumulate some paste from its rubbing against the upstanding rear flap. If so, no 25 harm is done, for it may apply a little of this paste to the outside of the leading flap, while the fact that it is itself pasty prevents it from removing paste from the rear flap to any undesirable extent. The brush 59 operates 30 only on the clean back of the rear flap, and thus leaves the tip clean. Both of these brushes revolve continuously and are therefore susceptible of performing their functions at a high rate of speed. They turn 35 synchronously with the arrival of each cigarette within their respective fields of action. As practically all of the parts of the mechanism move continuously, and as the motion of those parts whose action is 40 reciprocating is but slight and the reciprocating parts themselves light in weight, the machine has possibilities of running at very high speed with steady perfection of operation, thus producing a large output per machine 45 with no greater cost for labor of attendance than is required of a machine having a much smaller output. The arrangement clearly illustrated in Fig. 12 contributes to this uniformity, by which several cigarettes are always waiting at the 50 position A, and back of it, ready to be thrust forward into the position B by the swiftly moving belt 34 as rapidly as the cigarette in position B is moved by the successive 55 pairs of pins 44, 44' on the main drum 43.

It will readily be understood that variations and adjustments may be made without departing from the scope of the invention and patent.

60 I claim as my invention:

1. The combination in band applying mechanism of a holder for a supply of rod-shaped articles; a conveyer belt, means to transfer the articles to it singly, one behind 65 the other, end to end; a stop for the leading

article; wrapping mechanism moving continuously adjacent to said leading article and having means to seize and remove said articles in a transverse direction; said belt slipping idly under the articles while they 70 are stopped and projecting them forward to replace the leading article immediately upon its removal.

2. The combination in band applying mechanism of a tray and means for feeding 75 rod-like articles endwise thereto, including a conveyer belt adapted to slip idly under a line of the articles when their movement is obstructed, and to propel them into said tray when the obstruction is removed, 80 and a drum adapted to seize the leading article and to seize a wrapper; and to convey these two by continuous motion through a course where they are wrapped together.

3. The combination in band applying 85 mechanism of a continuously moving element having means for seizing a rod-shaped article and a wrapper for it in passing where these are supplied, and having a socket conforming to the shape of the article 90 and adapted to receive both the article and wrapper, thereby partially wrapping the article; and supplementary means for completing the wrapping, mounted adjacent to the course of the socket after it receives the article and wrapper.

4. The combination in band applying mechanism of a continuously moving element having means for seizing a rod-shaped article and a wrapper for it in passing where 100 these are supplied; means pressing the middle of the wrapper about a part of the article, leaving the ends thereof projecting; and supplementary wrapping means comprising continuously rotating, flexible wipers 105 mounted adjacent to the subsequent course of the article and wrapper.

5. The combination in band applying mechanism of a continuously moving element with means moving with said element 110 to dislodge an article resting in a stationary position adjacent to its course; means to assemble a wrapper with said article on said moving element and means to complete the wrapping while the article and wrapper are 115 moving with said element.

6. The combination in band applying mechanism with a drum and wrapping mechanism for rod-shaped articles, of pins projecting radially from the drum; and a 120 tray adjacent to the surface of the drum having openings in its bottom through which said pins may pass to engage and remove an article therefrom to the drum.

7. The combination in band applying 125 mechanism with a drum and wrapping mechanism for rod-shaped articles, of pins projecting radially from the drum; a tray adjacent to the surface of the drum having openings in its bottom through which said 130

- pins may pass to remove an article therefrom to the drum; and stationarily mounted devices for standardizing the position of the article on the drum at the time of transfer.
- 5 8. The combination in band applying mechanism with a drum and wrapping mechanism for rod-shaped articles, of pins projecting radially from the drum; a tray adjacent to the surface of the drum having 10 openings in its bottom through which said pins may pass to remove an article therefrom to the drum; and detents adapted to engage the tops of the ends of the article to correct its position as it is transferred.
- 15 9. The combination in band applying mechanism with a drum and wrapping mechanism for rod-shaped articles, of pins projecting radially from the drum; a tray adjacent to the surface of the drum having 20 openings in its bottom through which said pins may pass to remove an article therefrom to the drum; the said drum having a shallow socket extending parallel to its axis to receive the article, and there being a stationary detent to engage the top and standardize the position of any article not lying flat in said socket.
- 30 10. The combination in band applying mechanism with a drum and wrapping mechanism for rod-shaped articles, of pins projecting radially from the drum; a tray adjacent to the surface of the drum having 35 openings in its bottom through which said pins may pass to remove an article therefrom to the drum; the said articles lying parallel to the axis of the drum, and there being on the drum a socket and end-stop for the article; a strip support holding the wrapping material in registry with said 40 stop; and a lever actuated by a part moving with the drum to push the cigarette in the socket endwise to said stop.
- 45 11. The combination in band applying mechanism of a continuously moving drum and wrapping mechanism for cigarettes with means to hold a supply strip of wrap- 50 per in registry with the face of the drum, and means to move cigarettes singly into position above the drum and said strip; there being an opening under the leading end of the cigarette and a tray beneath it but above the said supply strip.
- 55 12. The combination in band applying mechanism of a continuously moving drum with means to wrap the tips of rod-shaped articles carried thereby; means to support said articles singly over the drum with their tips projecting beyond the face of the drum; means to hold a supply strip of wrapping 60 material beside the face of the drum and under the said projecting tip; and means on the drum to seize the article in passing and to seize the end of the supply strip in passing and assemble the two together on 65 the drum; and means acting thereafter to

sever the end of the strip and to wrap the severed portion about the article while the drum continues in motion.

13. The combination in band applying mechanism of a continuously moving element having means for seizing an article and its wrapper in passing, and a socket adapted to receive the article and its wrapper; the article-seizing means including pins upstanding from the drum behind the socket, 75 and the wrapper seizure comprising a clamp adapted to pinch the wrapper on the forward edge of the socket.

14. Band applying mechanism, comprising in combination a continuously moving 80 socket-member; means to supply articles singly to a definite location, and means to hold a supply strip of wrapping material in a definite location; means whereby the said socket member seizes such article and 85 wrapper, its socket enveloping approximately half of the article, with flaps of the wrapper projecting toward the edges of the socket; and supplementary wrapping means at fixed positions later in the course of the 90 moving socket member adapted to act upon the portions which project from the socket.

15. The combination in band applying mechanism of a continuously moving drum and means moving therewith to take from 95 positions of rest an article that is to be wrapped and a strip of wrapping material; means releasing the strip when a predetermined amount has been drawn; severing means acting on the strip after such release; 100 and wrapping mechanism.

16. The combination in band applying mechanism of a continuously moving drum and means moving therewith to take an article from a position of rest; means on 105 the drum to seize a strip of wrapping material; a stationary cam controlling the place and duration of seizure; severing mechanism, acting on the strip after the termination of its seizure; and wrapping mech- 110 anism.

17. The combination in band applying mechanism of a continuously moving drum having means to seize from a position of rest and carry with it articles whose tips are to 115 be wrapped; an element moving with the drum and having a socket conforming to the shape of one side of the article that is to be wrapped; mechanism moving with the drum for seizing the end of a strip of wrapping 120 material overlying the socket; means to release and to stop the movement of the strip; means to sever the strip when the movement of the article and socket has continued a predetermined amount thereafter; means to 125 assemble the article and severed portion in said socket thereby beginning the wrapping; and means to complete the wrapping during further movement of the drum.

18. The combination in band applying 130

mechanism of a continuously moving drum with means to seize from a stationary position an article; means to seize, draw forth and release a strip of wrapping material for 5 it; means to sever the strip when again stationary at the place where its leading end formerly was; the position of the portion that is to be severed being adjusted with respect to the article during the interval between 10 said release of the strip and severing of the strip.

19. The combination in band applying mechanism of a continuously moving drum with a multiplicity of mechanisms thereon 15 similar to each other, spaced equally apart and each adapted to seize an article and a wrapper strip and then to release the strip; strip severing mechanism; and a cam operating it rotating once for each of said equal 20 spaces and operating the said mechanism each time to sever the strip at a predetermined interval after the said release thereof.

20. The combination in band applying mechanism, with a continuously moving 25 drum, of means to apply adhesive to a strip of wrapping material; means on the drum to seize an article and the end of said strip, and to position the article in adhesive contact with said strip; means to sever a predetermined length of the strip, the severed portion being carried forward by adhesion 30 to said article; and mechanism for wrapping the adhering portion around it.

21. The combination in band applying 35 mechanism with a continuously moving drum, and means to assemble an article and the end of a strip of wrapping mate-

rial together thereon, of strip severing mechanism, and means moving it into and out of the path of the said assembled articles, said moving means being connected positively with the drum, whereby synchronously with the passage of said assembled articles it severs the strip at a predetermined interval after each such passage. 40

22. The combination in band applying mechanism of a continuously moving drum; severing mechanism for the strip of wrapping material; continuously rotating means imparting to it intermittently a movement 45 to and from the strip position; and means arranged in multiple at equal spaces on the drum to seize an article and said strip and assemble them together on the drum before each such intermittent action. 50

23. The combination in band applying mechanism of a continuously moving drum having a multiplicity of similar article and strip seizing mechanisms equally spaced; a cam connected to rotate once with the passage of each said mechanism; a connecting rod reciprocated by said cam; multiplying gearing, moved by said connecting rod; and strip severing mechanism actuated angularly thereby through a considerable arc to 55 and from the strip; whereby slight throws of the cam repeatedly permit passage of article and strip and then sever the strip. 60

Signed by me at Boston, Mass., this 25th day of June, 1914.
